UNITED STATES PATENT OFFICE.

WILLIAM Q. OLDEN, OF CHICAGO, ILLINOIS, ASSIGNOR OF ONE-HALF TO HIMSELF AND ONE-HALF TO ROBERT B. CAMPBELL, OF JOLIET, ILLINOIS.

DUMP-CAR.

No. 866,676.

Specification of Letters Patent.

Patented Sept. 24, 1907.

Application filed December 12, 1906. Serial No. 347,473.

To all whom it may concern:

Be it known that I, WILLIAM Q. OLDEN, a citizen of the United States, residing at Chicago, in the county of Cook and State of Illinois, have invented certain new 5 and useful Improvements in Dump-Cars, of which the following is a specification, reference being had to the accompanying drawings.

This invention relates to dump-cars of that class in which the material is discharged through a large central 10 opening which is normally kept closed by suitable swinging doors.

The object of the invention is to provide an improved door construction and improved means for operating such doors. I accomplish these objects by the construction shown in the drawings and hereinafter specifically described.

That which I believe to be new will be pointed out in the claims.

In the drawings,—Figure 1 is a longitudinal section 20 through a portion of a car, in which my improvements are embodied, such section being taken at line 1—1 of Fig. 3; Fig. 2 is a horizontal section taken at line 2—2 of Fig. 3; Fig. 3 is a vertical section taken at line 3—3 of Fig. 2, showing the doors in their closed position; Fig. 4 is a view similar to Fig. 3 but taken at line 4—4 of Fig. 2; Fig. 5 is a view similar to Fig. 3 but showing 25 the doors opened to permit the discharge of material from the car; and Fig. 6 is an enlarged detail, being a perspective view of that member or part of the toggle-lever mechanism that carries the counter-weight.

In the drawings I have shown a construction of car-body which forms the subject-matter of my pending application, Serial No. 344,080, filed November 19, 1906. I shall, therefore, describe such car construction briefly and only so far as is necessary to an understanding of my present invention.

10 indicates the side sills of the car, which, as shown, are formed of channel-irons, and 11 are the sides, preferably formed of girder construction.

40 12 indicates plates extending longitudinally of the car at each side of the car.

13 indicates inclined floor plates at the ends of the car, and 14 inclined floor plates at the sides of the car. The lower ends of these several inclined floor plates are 45 turned down into substantially vertical position, as clearly shown in Figs. 3, 4 and 5, and form the side walls of a large central opening 15 through which the material from the car is discharged.

16 indicates a bolster extending transversely of the 50 car near one end. A like bolster, of course, is to be provided at the other end of the car.

17 indicates center sills, two of such sills being provided at each end of the car. The sills at each end are

spaced apart so that provision is made between them for the usual draft-rigging. Each pair of center sills 55 extends inward from the end of the car and terminates near the inner end of the long central opening 15, before referred to. 18 indicates a plate extending transversely of the car next to the inner face of the bolster 16 and lying upon and secured to the said center 60 sills 17.

The various parts of the framework of the car are suitably riveted together—all as more specifically set forth in my said pending application.

19 indicates four channel-irons, two at each side of 65 the central opening 15, each channel-iron extending from one of the side sills 10 inward and terminating at its inner end near one of the side walls of such central opening. Each channel-iron 19 is to be secured in place by suitable rivets and brackets to its adjacent 70 side sill 10 and by rivets to one of the longitudinally-extending plates 12. In the construction shown, these channel-irons are shown as each located so as to be about midway between one end of said central opening and its longitudinal center, as best shown in Fig. 1. 75 20 indicates plates, one of such plates being securely riveted to the face of each of the channel-iron supports 19 and projecting below such channel-iron support, as clearly shown in Figs. 3, 4 and 5. These channel-irons and plates that are secured thereto form the supports 80 for the doors that close the large central opening 15 and also for the toggle levers used in operating such doors and hereinafter described. Two doors are employed for closing said central opening, each door, in the construction shown, standing, when closed, at an angle of 85 about forty-five degrees and substantially in line with the inclined side floor sections 14. These doors are indicated by 21. The plate forming the wearing surface of each door is turned at its upper end, as at 22, so as to project slightly, when the door is closed, below the 90 side wall of the large central opening, and has a turned lower end 23,—such turned lower end 23 being substantially vertical, when the doors are closed, whereby the inner faces of such turned ends will abut, as clearly shown in Figs. 3 and 4, and thus insure a tight joint. 95 To the under face of each door 21 are securely riveted a number of Z-shaped angle-irons, against the lower face of which are suitably secured two beams 25, preferably of angular shape. Each door beam is pivoted at 26 to one of the supports formed by a channel-iron 19 and 100 plate 20.

27 indicates an arm pivotally attached at its lower end by a pivot 28 to the lower end of one of the beams 25.

29 indicates two other arms, shorter than the arms 27, each of said arms 29 being pivotally attached at its outer 105 end to one of the depending plates 20 that is carried by

one of the channel-irons 19. Each arm 29 is provided, as clearly shown in Fig. 6, with a hub or boss 30 on its outer face, which hubs or bosses come against the inner faces of the depending plates 20 and thereby hold the arms 29 sufficiently away from the plates 20 to permit the arms 27 that are connected with the arms 29 to move freely past such plates 20, when the doors are open, as shown in Fig. 5. The arms 29 are pivotally attached to their respective plates 20 by pins 31 passing through 10 their hub portions 30 and said plates.

32 indicates the pins that pivotally unite the arms 27 and 29 together, the openings through the arms 29 for such pivot pins being located a little distance from the inner ends of such arms 29, as clearly shown in Fig. 6. 15 Each pair of arms 27 and 29 constitutes a pair of toggle levers. The long arms 27 of the double toggle that is thus formed for operating each door are formed separate from each other, but the shorter arms 29 are connected together, and the connecting means employed is a very 20 heavy bar 33, which, in the construction shown, is of angular form, and the function of which is to act as a counter-weight to close, or assist in closing, the doors after the load has been discharged from the car.

34 indicates ears formed on the face of the angular 25 counter-weight 33, between which is pivotally secured by a pin 35 the lower end of a rod 36 that extends upward through a suitable opening 37 in one of the plates 12 and is pivotally connected by a pin 38 to one end of a bell-crank lever 39 that is pivoted at 40 between a pair 30 of supports 41 that are suitably connected to the upper face of the longitudinally-extending plate 12—these supports 41 being, in the construction shown, formed of angle-irons.

42 indicates a connecting bar, which, for purposes of 35 strength, is made of inverted T-shape. This bar is pivotally connected at 43 with one arm of the bell-crank lever 39 and at its other end is connected at 44 with one end of a cross-head 45.

There are two sets of operating devices, one set for 40 each door, and each is constructed in the manner already described. The two connecting rods and the parts to which they are respectively connected are best shown in Fig. 2.

46 indicates suitable guiding supports extending between one of the bolsters 16 and the end of the car upon which the cross-head 45 rests.

47 indicates an air-cylinder, in which is located a piston, as usual, to which piston is connected a piston-rod 48, the outer end of which is secured to the central portion 50 of the cross-head 45. This cylinder, in the construction shown, is suitably secured in an open framework 49 that is supported between the adjacent body-bolster 16 and the end of the car.

50 indicates a pipe, through which air under pressure 55 is supplied to the cylinder. This pipe connects with a suitable source of supply, which may be either a train pipe leading from the engine to which the car is attached or the auxiliary reservoir of the ordinary brake system.

60 I have called attention to the fact that the doors, when in their closed position, as shown in Figs. 3 and 4, are sharply inclined. This arrangement of the doors increases quite considerably the capacity of the car, but it is, of course, necessary that there be a protecting device 65 at the ends of the doors to prevent the escape of ma-

terial at those points. I therefore provide opposite each end of the doors a plate 51 of triangular shape, which is secured against the ends of the center sills 17,—short angle-bars 52 (see Fig. 4) being employed to effect this connection,—and said plates are further secured by riveting their upper edges to the downwardly-turned edges of the inclined floor sections 13 that form the end walls of the large central opening 15. The inclined edges of these triangular plates are turned inward to form flanges which act not only to stiffen the plate but 70 serve as surfaces against which the face plates of the doors abut, thereby forming a tight joint. These flanged edges of the triangular plates are indicated by 53.

With the doors in their closed position, as shown in 80 Figs. 3 and 4, and with the car loaded with material which it is desired to discharge through the opening 15, air will be admitted to the cylinder 47 and, of course, move the piston therein and through the piston-rod 48 force the cross-head 45 inward or toward 85 the center of the car. Such movement of the cross-head, of course, is transmitted through the connecting bars 42 to the bell-crank levers 39, causing such bell-crank levers to turn upon their pivots 40 with the result of drawing up the rods 36 which are pivotally attached, as before described, to the bell-crank levers. The upward strain of these rods 36 on the short arms 29 of the toggle members causes the ends of the toggle arms that are pivoted together to turn on their pivots 32, and as such pivotal points 32 are raised out of line 90 with the pivotal points 28 and 31 the two doors will, of course, commence to open or move away from each other, and the weight of the load upon these doors will greatly aid in pushing back such doors. The continued pushing on the bell-crank levers by the bars 100 42, and the tendency of the descending load to spread apart the doors, will very quickly cause the doubling up of the toggle members 27 and 29, notwithstanding the heavy force of the counter-weight device 33 that is being exerted against such movement. The doors 105 will continue swinging open until stopped in a substantially vertical position, as indicated in Fig. 5. The stopping of the doors in this position is secured by the longer face of the counter-weight 33 being brought to rest against the under face of its adjacent longitudinal 110 plate 12. Upon the closing of the doors the bell-crank levers will be brought in contact with the plates 12, thus providing a positive stop for the downward movement of the toggle-levers. As is best shown in Fig. 5, when the doors are opened the inclined upper ends 22 115 of the wearing plates of the doors will project in under the side edges of the large discharge opening so as to properly deflect any material that might otherwise have a tendency to pass to one side or that would accumulate on the door if the inner ends of the doors were 120 square. Furthermore, it will be noticed by reference to said Fig. 5 that owing to this inclination of that end of the wearing plate of the door and also owing to the pivot pins 26 being set back or to one side of the edge of the discharge opening, a considerable space is left 125 between the upper edge of the door and the adjacent side of the discharge opening, through which a rod or other tool can be inserted in case any obstructions form there that need dislodging.

From the foregoing, it will be evident that in prac- 130

tice air pressure sufficient to move the operating parts so that the toggle connection is broken is really all that is required; for, after such breaking of the toggle—that is, after the members 27 and 29 have their pivot 5 pins 32 raised out of line with the other pivot pins 28 and 31—the weight of the load will generally be sufficient to overcome the weight imposed by the counter-weight device 33 so that the parts will be quickly moved into the position shown in Fig. 5. The air 10 pressure, however, is to be kept on during the unloading operation, in order that the doors may not be prematurely closed. For it is to be understood that the counter-weight device 33, extending as it does far beyond the pivots 32, exerts pressure enough, when the 15 devices are not supported by air pressure from the cylinder, to force the toggle levers down and as a result of such forcing down cause the doors to close. From this it is evident that under normal conditions all that is necessary to be done to close the doors is to 20 destroy the air pressure in the cylinder in the usual manner, and immediately upon its occurring the counter-weight serves to close the doors instantly, as described.

In order that the doors may be opened or closed 25 when through any cause the air pressure device is inoperative, I provide hand-operated means for moving the bars 42 toward the center of the car to cause an opening of the doors, or in the reverse direction to cause a closing of the doors. These hand-operated means are 30 provided at the same end of the car as the air cylinder 47 and consist of two horizontal shafts 54, which, in the construction shown, are in line with each other, and each of which is provided on its inner end with a hand-wheel 55. Each shaft is provided with two chains, one 35 of which, 56, is fast at one end to said shaft and passes over a pulley 57 suitably journaled in brackets attached to the bolster 16 and the other end of said chain is attached to one end of the cross-head 45. The other chain referred to is indicated by 58 and is also made 40 fast at one end to the shaft, and after passing over a pulley 59 that is suitably secured near the end of the car, is attached at its other end to said cross-head 45 a short distance from the end of the cross-head. Two of these hand devices are provided, as stated. One of them is 45 indicated in full lines in Fig. 2, while the other is represented by broken lines, except that at the side where the device is indicated in broken lines portions of the two chains 56 and 58 are shown in full lines. It is evident that when these shafts 54 are turned in one direction one set of chains will be wound around the shafts and exert a pull on the cross-head that will move it 50 toward the end of the car, while the other set of chains will unwind from the shafts, but when the shafts are turned in the reverse direction the set of chains that 55 had before exerted the pull on the cross-head will unwind from the shafts, while the other set of chains will wind up thereon and exert a pull on the cross-head in the other direction. By these means the doors can be opened or closed by hand. Any suitable ratchet device 60 may be employed in connection with the hand-wheels and shafts for holding them against rotation when the doors have been fully opened so that the doors may not be prematurely shut by reason of the force exerted on the toggle devices by the counter-weight.

65 By my improved construction I provide doors that

can be opened with but slight effort, and when opened will remain in a fixed position so as to act to properly direct the material being discharged, and which are capable of automatically closing by reason of the construction and arrangement of the counter-weight apparatus attached to and carried by the toggle-levers pivotally attached to the doors. Furthermore, by reason of the location of the door-operating bars and bell-crank levers connected therewith beneath the inclined floor sections at the sides of the car, such parts are protected and are also easy of access for any purpose. The arrangement of the cylinder and the cross-head connected thereto, as well as the auxiliary hand-operating devices, beneath the inclined floor section at one end of the car also provides for these parts being protected as well as making them readily accessible.

That which I claim as my invention, and desire to secure by Letters Patent, is,—

1. In a dump-car having a discharge-opening therein, the combination with a pivoted door for said opening, of toggle-levers for holding said door closed, means for breaking the toggle to permit said door to open, and a counter-weight carried by one of the toggle-levers and adapted to force said door closed after the release of the power that had been applied for opening the door.

2. In a dump-car having a discharge-opening therein, the combination with a pivoted door for said opening, of toggle-levers for holding said door closed, means for breaking the toggle to permit said door to open, and a counter-weight carried by one of the toggle-levers and adapted to force said door closed after the release of the power that had been applied for opening the door, said counter-weight projecting beyond the pivot that connects said toggle-levers together.

3. In a dump-car having a discharge-opening therein, the combination with a pivoted door for said opening, of two pairs of toggle-levers, one member of each pair of which is pivotally connected with the door and the other members of which are connected to a suitable support, and a counter-weight extending between and connecting said last-named members and adapted to force said door closed after the release of the power that had been applied for opening the door, and means for breaking said toggle.

4. In a dump-car having a discharge-opening therein, the combination with a pivoted door for said opening, of two pairs of toggle-levers, one member of each pair of which is pivotally connected with the door and the other members of which are connected to a suitable support, and a counter-weight extending between and connecting said last-named members and adapted to force said door closed after the release of the power that had been applied for opening the door, said counter-weight projecting beyond the pivots that connect said two pairs of toggle-levers together, and means for breaking the toggle.

5. In a dump-car having a discharge-opening therein, the combination with a pivoted door for said opening, of two pairs of toggle-levers, one member of each pair of which is pivotally connected with the door and the other members of which are connected to a suitable support, said last-named members being united by a counter-weight device adapted to cause a closing of the door after the release of the power that had been applied for opening the door, a rod pivotally attached to said counter-weight device, and means for exerting an upward pull on said rod to break said toggle.

6. In a dump-car having a discharge-opening therein, the combination with a pivoted door for said opening, of two pairs of toggle-levers, one member of each pair of which is pivotally connected with the door and the other members of which are connected to a suitable support, a member of one of said pairs being connected to the corresponding member of the other pair, a rod pivotally attached to the device connecting said last-mentioned members, and means for exerting an upward pull on said rod to break said toggle.

7. In a dump-car having a discharge-opening therein,

- the combination with a pivoted door for said opening, of
two pairs of toggle-levers, one member of each pair of
which is pivotally connected with the door and the other
members of which are connected to a suitable support, a
5 member of one of said pairs being connected to the corre-
sponding member of the other pair, a rod pivotally at-
tached to the device connecting said last-mentioned mem-
bers, a bell-crank lever to which said rod is also pivotally
attached, and means for rocking said bell-crank lever to
10 raise said rod and break said toggle.
8. In a dump-car having a discharge-opening therein,
the combination with a pivoted door for said opening, of
toggle-levers connected with said door and a suitable sup-
port, a rod pivotally attached to a member of said toggle-
15 levers, a bell-crank lever to which said rod is also pivotally
attached, a bar extending longitudinally of the car and

terminating near one end of the car, and means at that
end of the car for moving said bar.

9. In a dump-car having a discharge-opening therein,
20 the combination with two pivoted doors adapted to close
said opening, of a pair of toggle-levers pivotally connected
with each door, a rod pivotally attached to a member of
each pair of said toggle-levers, bell-crank levers to which
25 said rods are pivotally attached, bars connected to said
bell-crank levers and extending longitudinally of the car
and terminating near one end of the car, a cross-head con-
necting the ends of said bars, and means for moving said
cross-head.

WILLIAM Q. OLDEN.
